COMBINED BENCH AND TABLE FRAME UNIT

Earl L. Richardson, Chula Vista, Calif.

Application June 12, 1953, Serial No. 25,468

Term of patent 14 years

(Cl. D33—14)

To all whom it may concern:

Be it known that I, Earl L. Richardson, a citizen of the United States, residing at Chula Vista, in the county of San Diego and State of California, have invented a new, original, and ornamental Design for Combined Bench and Table Frame Unit, of which the following is a specification, reference being had to the accompanying drawing, forming part thereof, and wherein:

Figure 1 is a perspective view of a combined bench and table frame unit showing my new design;

Figure 2 is a top plan view thereof;

Figure 3 is a side elevational view thereof, with

a second identical but reversely positioned frame unit, and table and bench tops being shown in dotted lines for purposes of illustration only.

I claim:

The ornamental design for a combined bench and table frame unit, as shown and described.
